HYDROELECTRIC TREATMENT PLANT
WITH AIR SUPPLY

Fred Landauer, Rockville Centre, N. Y.

Application October 21, 1947, Serial No. 781,123

7 Claims. (Cl. 128—370)

1

The present invention relates to electro-therapeutic treatment plants and more particularly to a plant or apparatus for hydro-electric treatments of certain ailments, such as rheumatic and related conditions.

This application is a continuation-in-part of my U. S. application Ser. No. 530,633, filed April 12, 1944, now abandoned.

The present application differs insofar from said abandoned application in that it contemplates the establishment of an electric current flow between two electrodes while the thereby obtained electric field is simultaneously subjected to the influence of a fluid or gas stream directed substantially transversely to said electric field.

The therapeutic effect of an electrically charged bath on parts of the human body immersed therein may be brought about by thermal action which improves blood circulation by heating the tissues; by physiological action through stimulation of the nerve cells; and by chemical action through the introduction of a medicinal agent into the bloodstream. The efficiency of the treatment depends not only on the magnitude but also on the nature of the electric current employed. Thus, in the case of alternating or pulsating current, the stimulating effect on the nerve cells will generally dominate, whereas a direct current will produce better chemical results.

As the current passes from one electrode to the other through the bath liquid and the body or body part to be treated, there will be an intense change of ions and electrons at the contact surfaces of the liquid and those areas of the skin which lie intermediate the electrodes immersed in the water or other bath liquid. However, it will not be possible for all portions of a body immersed in the liquid to get the full benefit of the treatment.

It has been found that the above disadvantages may be overcome and the therapeutic effect of the hydro-electric bath increased by modifying the distribution of electrical charges in the liquid through the use of what may be termed, in analogy with thermal processes, "electrical convection." The method used to obtain this effect may comprise the steps of isolating charged particles of the bath liquid (e. g. water) by means of a gas stream (e. g. air) and utilizing said gas stream to convey the charged particles to points of different electrical potential where they may alter the electrical condition of the bath or impinge directly and locally upon the immersed body part.

It is, therefore, an object of the present inven-

2

tion to provide means for obtaining improved therapeutic effects of a hydro-electric bath by introducing into the bath liquid a fluid stream which may be continuously or intermittently produced.

It is a further object of the present invention to provide means for simultaneously producing an electric current flow as well as a fluid flow or stream within the bath liquid to thereby enhance the treatment conditions of the hydro-electric bath.

It is another object of the invention to provide means for combining the effects of a direct current with those of a pulsating or alternating current in a hydro-electric bath.

More particularly, it is an object of the present invention to provide nerve-stimulating electro-mechanical action at the surface of the skin of an immersed body or body part while at the same time subjecting the underlying tissues to the effects of a mainly uni-directional current.

Yet another object of the invention is to provide a method of enhancing the electro-chemical treatment effect upon an object immersed in a conductive liquid and exposed to the action of electric current passing through said liquid.

Still a further object of the invention is to provide method and means for influencing the electrical conditions prevalent between conductors immersed in a conductive liquid bath preferably containing a chemical, by the introduction of a stream of a substantially electrically non-conductive fluid which is directed angularly with respect to the flow of the electric current between said conductors.

The above and other objects and advantages may be best understood from the accompanying drawing and the following disclosure which sets forth how the invention may be carried out, and it is further intended that there be included as part of the invention all such obvious changes and modifications thereof as would occur to a person skilled in the art to which this invention pertains and as would fall within the scope of the claims.

In the drawing:

Fig. 1 illustrates an apparatus by which the invention may be carried into effect;

Fig. 2 shows a modification of the apparatus of Fig. 1; and

Fig. 3 represents a further modification of the apparatus or treatment plant embodying the invention.

Referring now more particularly to the drawing, there is shown in Fig. 1 a vessel or tank 10 of

insulating material which vessel may be of round, square or any other desired configuration. Secured to the inner faces 10a, 10b of the opposite walls of vessel 10, there is shown a pair of electrodes 11, 12 having opposed polarities and which are connected by way of respective terminals 13, 14 with a source 15 of electric current. Source 15 has been shown in Fig. 1 as a battery, but any other convenient type of power supply may be used.

A liquid 16, preferably an aqueous solution containing a medicinal agent, is placed in tank 10 to a level well above the top of the electrodes 11, 12. As a support for the body or body parts to be treated and as a protection therefor from direct contact with electrodes 11 and 12, there is suspended from the rim 10c of tank 10 a shield or rest means 17 which may be made of insulating material.

Mounted on the bottom of the tank 10 is a swivel head or injecting means 18 which serves to introduce a fluid, for instance in form of a gas, into the tank, said injecting means being connected to a suitable pump or blower (not shown) by way of conduit means, such as a pipe 19. Injecting means 18 terminates into two nozzles 20, pivoted about an axis 21 (as indicated by arrows) for the supply of said fluid passing through pipe 19 for discharge transversely to the electric current flow when established between electrodes 11 and 12 and through the bath liquid 16. This fluid may consist of air or like medium and will rise in the form of two substantially conical streams 16a, 16b from the discharge nozzles 20 toward the surface of liquid 16.

The introduction or injection of the gaseous fluid into the liquid 16 will give rise to the following phenomenon: Isolated water particles entrained by the air stream on its passage through the liquid will be charged with a polarity corresponding to that of the nearer of the two electrodes (e. g. 12) and will be attracted toward the opposite electrode (e. g. 11) while being carried and displaced in upward direction by the air stream. The cage or shield 17 of insulating material will not alter materially the course of these particles which subsequently impinge upon the limb or body part (not shown) which rests on the cage 17 and is held at substantially ground potential. The impingement of these particles upon the skin of the patient will not only result in a mechanical massaging action, but will also have the stimulating effect of many small electric charges entering and leaving the body at locally distributed points. By suitably adjusting the two discharge nozzles 20, the two air-streams, respectively, discharged thereby may be caused to overlap in such manner that their effect will be greatest on those areas which get the least benefit from the direct current passing between electrodes 11 and 12.

In the embodiments of Figs. 2 and 3 in which elements corresponding to certain parts in Fig. 1 have been indicated by the same reference numerals, the head or injecting means 18 has been replaced by an agitator 22 of which only the lower part is shown in Fig. 2, the complete device being illustrated in Fig. 3. A turbine housing 23 provided at the bottom of a pipe 24 has an intake opening at 25 and a discharge opening at 26. An impeller wheel (not shown) is disposed within the housing 23 and is driven from a motor 27 by means of a shaft extending within the pipe 24.

An air tube 28 extends above the level of liquid

16 and has its outlet positioned in front of the discharge opening 26, the air being entrained by the liquid which is set in motion through the impeller wheel and issues at 26 from the housing 23. An air stream is thus created which carries with it occluded or isolated water particles charged with the polarity of electrode 12, these particles tending toward electrode 11 while travelling with the air stream along a predetermined, arcuate path 16c toward the surface of the liquid. Somewhere along this path the electrically charged particles are likely to encounter the immersed body or body parts upon which they impinge, as described in connection with Fig. 1.

Referring now more particularly to Fig. 3, it will be seen that protective cage 17 has been replaced by two perforated guard members or shields 29, 30 which may be of metal since they are neither in contact with the electrodes 11, 12 nor interposed in the path of the air stream. The vessel 10 is formed with an annular extension 31 resting upon the rim of an outer tank 32 which is spaced from tank 10. The interior of vessel 10 communicates with the outer tank 32 by way of an overflow opening 33, tank 32 being provided with a drain 34 through which excess liquid from the inner tank 10 may be removed. A plug 35 covers a drain hole 36 in the bottom of vessel 10. The outer tank 32 is further equipped with an outlet nipple 37 which, in combination with drain 34 permits the circulation of hot water or the like within the space between tank 32 and tank 10 whereby the liquid 16 may be held at a suitably elevated temperature.

The motor 27 is carried on a bracket 38 secured by means of a set screw 39 to a rod 40 which is pivoted at 41 on a standard 42. Standard 42 is slidably held in a sleeve 43 and may be shaped to provide a rack for cooperation with a pinion (not shown), the latter being operable by means of a crank 44 for the purpose of raising and lowering the agitator 22 within the tank 10. Thus, it will not only be possible to vary the operative position of housing 23 in a vertical direction, but also to swing the entire device 22 about its pivot 41 into an inoperative position, as indicated in dot-dash lines.

The unit comprising motor 27, agitator 22 and tube 28 may also be mounted on a separate carrier (not shown) positioned outside of tank 32 for insertion therein and for displacement thereto.

The invention is also applicable to other fields of the industry where it is desired to change or influence the electro-chemical treatment which results from the employment of two electrical conductors immersed in a conductive bath liquid by the introduction of a fluid flow of non-conductive character into said bath liquid at a predetermined angle with respect to the current flow established between said conductors.

It can thus be seen that there has been provided in accordance with this invention an electro-therapeutic treatment plant comprising a vessel adapted to hold a liquid, a pair of electrodes extending along opposite walls of said vessel in a position as to be completely immersed in said liquid, a source of electric current for supplying current to said electrodes whereby a flow of electric current may be established through said liquid, perforated screen means supported on said vessel and adapted to form a rest for a body part when disposed between said electrodes within said liquid, and a distributor head disposed

within said vessel and at a location substantially intermediate said electrodes, said distributor head including a tube adapted to deliver a fluid under pressure to said head from without said vessel, said head being pivotally supported on said tube to direct a stream of said fluid through said liquid in substantially upward direction and transversely to said electric current flow.

While there have been shown, described and pointed out the fundamental novel features of the invention as applied to the above embodiment, it will be understood that various substitutions and changes in the form and details of the device illustrated and its operation may be made by those skilled in the art and without departing from the spirit of the invention.

Having thus described the invention, what is claimed as new and desired to be secured by Letters Patent, is:

1. The method of modifying the distribution of electrical charges in a bath liquid containing electrodes of opposed polarities which method consists in introducing a substantially non-conductive gaseous fluid stream into the bath liquid and at a location intermediate said electrodes, causing said fluid stream to isolate electrically charged particles of said liquid, and directing said fluid stream to convey said charged particles to points within said bath liquid having a potential different from that of said particles.

2. The method according to claim 1, wherein said fluid stream is directed onto a body part immersed in said bath liquid for therapeutic treatment.

3. The combination, in an electro-therapeutic treatment apparatus, of spaced apart electrodes adapted to be connected to an electric circuit and to have opposed polarities and adapted for contact with a treatment liquid, with gas injecting means positioned intermediate said electrodes and adapted to inject gaseous fluid into said liquid whereby said gaseous fluid is adapted to isolate electrically charged particles of said liquid,

a vessel containing said electrodes and said fluid injecting means, and rest means supported by said vessel and defining a space in said vessel for accommodating a body member to be treated, said rest means extending a predetermined distance into said vessel between said electrodes.

4. An apparatus according to claim 3, wherein said injecting means is spaced from said rest means and arranged below the latter.

10 5. An apparatus according to claim 4, wherein said injecting means is provided with adjustable nozzle means facilitating change of direction of the flow of gaseous fluid within the liquid contained in said vessel.

6. An apparatus according to claim 4, wherein said injecting means is positioned intermediate one of said electrodes and said rest means.

7. An electric treatment apparatus comprising a vessel adapted to contain a treatment liquid, a pair of electrodes within said vessel, said electrodes being adapted to establish an electric current flow within said liquid and being spaced from each other a sufficient distance to accommodate a body part for treatment therebetween, 20 gas discharge means arranged within said vessel intermediate said electrodes and adapted to direct a gas stream within said liquid transversely to said electric current flow, and shield means located in front of said electrodes and adapted to prevent said body part from contact with an electrode.
